APPARATUS AND SYSTEM FOR REGISTER-
ING WATCHMEN'S TOURS

Richard M. Hopkins, Rutherford, N. J., William J. Kleinknecht, Stratford, Conn., and Charles E. Whiteman, Richmond Hill, N. Y., assignors to American District Telegraph Company, New York, N. Y., a corporation of New Jersey

Application June 19, 1931, Serial No. 545,428

30 Claims. (Cl. 177—360)

This invention relates to watchman's tour and registry systems and apparatus and more particularly to improvements in systems of the class illustrated by the U. S. Patent 1,394,840 issued

5 Oct. 25, 1921 to C. C. Johnson and R. M. Hopkins.

According to said patent means are provided whereby a watchman is required to visit a number of preliminary stations in a certain sequence, for conditioning a key or register before said key 10 can operate a transmitting station to send a signal to a central or other office or place.

One object of the invention is to provide a system and apparatus of this kind in which one register key can be used to supervise the visits of 15 a larger number of stations than in the patented system.

Another object of the invention is to provide a system and apparatus of this kind in which one register key can supervise a number of tours 20 or tour sections of a single complete tour or circuit and after the completion of the tour sections send signals from transmitting stations associated with the respective sections.

Another object of the invention is to provide 25 adjustable devices in the apparatus to adapt the system for a number of preliminary and transmitting stations less than the maximum for which they are built.

Another object is to provide apparatus whereby 30 a single transmitting station and a single key may supervise a plurality of tour sections, sending a signal after the completion of each section.

Other objects of the invention are to improve generally the simplicity and efficiency of such 35 systems and apparatus and to provide apparatus of this kind which is economical, durable and reliable in operation, and economical to manufacture.

Still other objects of the invention will appear 40 as the description proceeds; and while herein details of the invention are described and claimed, the invention is not limited to these, since many and various changes may be made without departing from the scope of the invention as claimed 45 in the broader claims.

The inventive features for the accomplishment of these and other objects are shown herein in connection with an improved registry tour system which, briefly stated, includes a register or 50 key to be carried by the watchman, said key having a first nose, a second nose, and a lug, all, at times, movable relatively to each other to condition the key for successively fitting different stations of a plurality of series of preliminary 55 stations, each station of a series having charac-

teristic means for reconditioning the first nose only of a properly conditioned key for the next succeeding station only, and engageable with said noses for preventing such conditioning of a key when the key is not conditioned for such station. 5 One or more signal-transmitting stations are provided, to be visited after visiting each series, the transmitting station being controlled by a properly conditioned key for causing a signal, and having means for conditioning the first nose for 10 the next succeeding station, and the second nose for the next succeeding series, whereby the watchman is compelled to visit all stations of all series in sequence before a signal can be again transmitted from the transmitting station, thus providing for a large number of stations. 15

While in this specification and claims mention is made of registers, keys and stations and it is stated that one part is moved toward the other rather than vice versa, it is understood that these 20 words are used for designation and description and that for purposes of protection they are to be construed broadly enough to cover other analogous, apparatus and devices, and in general the terms are to be given broad interpretation when 25 possible for the purposes of protection.

In the accompanying drawings showing, by way of example, several of many possible embodiments of the invention,

Fig. 1 is a front elevation showing one form 30 of transmitter or signal transmitting station with cover door removed;

- 30 Figs. 33 to 37 are views of details of the arrangement of Figs. 31 and 32;
- Fig. 38 is a fragmental front view of still another arrangement of stepping disk.

35

The system as a whole

A brief idea of the system as a whole will first be very briefly indicated, after which the parts will be described in detail. The system comprises a register or key (Figs. 3 to 10), preliminary stations (Figs. 21 to 25), which have to be visited, in sequence, in order to condition the key for sending a signal at a transmitting station (Figs. 1 and 2).

The register or key has an inner nose 11, an outer nose 21 and a long lug 27 all, at times, movable relatively to each other for conditioning the key, and a plurality of characteristic means 13, 14, 32 for locking together the lug 27 and the cylinder 10 carrying the first nose. There are also means 43, 44, 45 (Figs. 4 to 6) for locking the first and second nose and lug together, and bumps 36 for unlocking them at one certain predetermined position of rotation of the lug 27 relative to the first nose 11.

55 Each station of the series of preliminary stations 1 to 9 (Figs. 18 and 19) has ribs 83 (Fig. 23) receiving the lug 27 and characteristic stop means 90 engageable with the noses for preventing the complete insertion of the key when the key is not conditioned to be received by the notches 92, 93 of that stop means, and means such as yieldably protruded balls 86, for unlocking the means 13, 14, 32 of the key when conditioned for the station, said ribs 83 serving, when the key and cylinder 10 are operated, to move the lug 27 relative to the inner nose 11 to condition the key for the next succeeding station.

One or more stations T (Fig. 19) and A to E (Fig. 18) are signal transmitting stations having notches 113, 124 (Fig. 1) 124, 170 (Fig. 20) adapted to receive the key when conditioned therefor and in said certain position of adjustment, such transmitting station having a signal transmitter clockwork controlled by the key and means 110 (Fig. 2) 115, 116 (Fig. 1) for relatively condi-

tioning the lug 27 and inner nose 11 for the next succeeding station, and means 121, 168, 173, 180 (Fig. 11) or 121, 250, 168 (Fig. 20) actuated by the inner nose for moving the outer nose 21 to condition it for the next succeeding station in series.

5 Each station conditions the key for the next station only, so that it becomes necessary to make a complete round before the same transmitter station can be operated again.

Now the various parts of the system will be described in detail.

The register or key

The key or register for our watchman's compulsory tour system comprises a main hollow cylinder 10 (Fig. 4) having at its forward end, an inner or lower digit actuating nose 11. Said cylinder has therein a number of perforation locations arranged in longitudinal rows equal angles apart and in annular series equal distances apart, perforations 13, 14 being provided at certain of said locations and omitted in others, so that each longitudinal row 13, 14 contains a different combination of perforations. A handle 25 15 (Fig. 3) is provided with a plug 16 (Fig. 4) secured fast by a protected pin 17 in the outer end of the cylinder.

The outer or higher digit nose

An annular enlargement 19 forming a shoulder at the inner end of the cylinder is formed to provide the arcuate inner nose 11 extending about 60° around and projecting slightly longitudinally from the inner end. An outer or higher digit outer nose sleeve 20 rotatably received on said cylinder and enlargement 19 is provided with outer nose 21 projecting about the same distance as the inner nose, and is provided at the inner edge with an inner shoulder engaging against said shoulder of the enlargement 19 to hold the sleeve in place.

A shell 25 held fast on the outer end portion of the cylinder by the pin 17 has its inner end part spaced from the cylinder for forming a deep annular space receiving the end portion 26 of a long lug member 26, 27, 28.

The long lug and tumblers

The long lug member 26, 27, 28 comprises a long cylindrical portion 26, 28 rotatably received on the cylinder between said sleeve and shell and in said space, and a long lug 27 extending from the shell to near said sleeve 20, said lug being provided with radial bores 29 having open reduced inner ends 30 registerable with said perforation locations and perforations 13, 14 when present.

Tumblers or plunger pins 32, 33 in said bores have reduced ends 32 adapted to protrude into, and lock in, respective registering perforations 13, 14 of the main cylinder, and heads 33 engageable with the reduced ends 30 of the bores to limit protruding movement, the tumblers being yieldably protruded by springs 34 compressed against said heads and the closed ends of the bores.

The outer-nose lock

Adjacent ends of said sleeve 20 and cylindrical portion 28 are provided with interior annular grooves 35 receiving bumps 36 of the main cylinder, said ends being reduced in diameter to form an outer bearing groove to receive a short lug member 38, 39 comprising a cylindrical portion 38 rotatably received in said outer groove, and a short lug 39 normally aligned with the long lug

27 and at times rotatable relative thereto and provided with radial bores 40 having open inner ends.

5 Springs 42 in the bores press plunger pins 43 respectively into one of the perforations 44 (Fig. 5) of the outer nose sleeve and a perforation 45 (Fig. 6) of the long lug member. Said bumps 36 are positioned to engage said plunger pins 43 after each complete rotation of the cylinder relative to the long lug, thereby releasing the outer or higher digit nose, so that it may be moved an increment on each revolution of the inner nose, thus multiplying the number of relative positions of the two noses for conditioning the key for a 10 large number of stations.

Automatic key-disabler and tell-tale

The rear end of said cylindrical portion 26 (Fig. 9) of the long lug is provided with an annular series of perforations 48 successively registerable with a perforation of the main cylinder 10, in which may engage a locking pin 50 movable in a transverse bore 51 in the plug 16. A spring 52 compressed between a collar 53 on the 15 pin and the cylinder 10 serves to retract the pin from the perforations 48 of the long lug member to permit relative rotation of the lug member and cylinder 10.

A longitudinal bore 55 in said plug 16 near one side thereof across the inner end of the transverse bore 51 terminates at its rear end in a laterally open enlarged recess 56 laterally closed by the main cylinder. A spring 57 compressed in said recess tends to slightly project an actuating pin 58 (Fig. 8) longitudinally slidable in said longitudinal bore 55 and provided with an inner head 59 to limit its projecting movement, and a normal diameter rear portion 60 normally engaging the locking pin to hold the latter in locking position, as in Fig. 4.

The intermediate part of said actuating pin is tapered in opposite directions to an intermediate reduced portion 62, and adapted when the actuating pin is forced into the bore, by normal engagement with the core 85 (Fig. 24) or 108 (Fig. 1) of a station, to engage the inner end of the locking pin to allow the latter to withdraw from the lug member to permit relative rotation of the lug member 26, 27 and cylinder 10, only when the key is all the way in the station.

The actuating pin has also a shallow tell-tale groove 63 therearound forming abrupt shoulders, between said reduced portion 62 and the outer end 65 of the pin, whereby if the actuating pin is pushed back too far, as by a person attempting to manipulate the tumblers, the locking pin 50 is trapped between said shoulders and the locking pin is locked in projected locking position.

Station indicia

An arrow (not shown) on the outer face 65 (Fig. 3) of the long lug 27, cooperates with a series of station indicia such as the letter "T" 65 on the handle (Fig. 3) and Arabic numerals 67, serving to indicate stations, arranged around the key shell 25 near the long lug, to indicate the position of the long lug relative to the shell and inner nose, and to indicate the stations which the inner nose 11 is positioned to fit. A series of tour section indicia, such as letters 68 arranged around the outer nose sleeve 20, and an index pointer 69 on the short lug member and associated with said series indicate the position of the outer nose relative to the lugs, thereby to indicate the tour sec-

tion of series of stations which the outer nose is positioned to fit.

Preliminary stations

Each regular preliminary station 75 (Figs. 21 to 25) may comprise a base 76 adapted to be secured to a wall or other support and carrying an approximately cylindrical outwardly tapering housing 77 having an outer flange 78 secured to the base, and an outer end wall 79 (Fig. 24) provided with a keyhole 80, 81 comprising a circular part 80 adapted to receive the cylindrical portions 20, 26 of the lug members and a radial part 81 adapted to afford a passage way for the lugs 27, 39. Interior parallel ribs 83 on the side wall 15 of the housing form a continuation of the radial part 81 as a passage way for the lugs 27, 39 and serve to hold the lugs against rotation.

A guide core 85 secured fast on said base axially of the base and housing is provided with radial 20 bores (as in said patent) disposed in a plane passing through the axis of the radial part of the keyhole. Said bores have outwardly opening reduced outer ends with which said row of perforations 13, 14 are registerable when the key is 25 inserted through the key hole the proper distance on the core; and springs compressed in each bore serve to yieldably protrude plunger balls 86 pressed by said springs against, and slightly projected from, the reduced ends, thereby to engage 30 and push back projecting tumbler pins 32, 33 of the key, thereby to unlock the cylinder 10 from the long lug 27.

Said casing 79 is provided with interior shoulders 87, 88 facing and near said base on which 35 are secured a back stop plate 90 provided with a central opening 91 receiving said core, and with arcuate notches 92, 93 beveled at the end as at 94 adapted to receive said noses 11 and 21 respectively, the notch 92 being long enough to allow 40 a lost-motion movement equal to the angle which the nose is to be advanced, while the outer notch 93 snugly receives the outer nose.

Operation at preliminary stations

The line 97 of arrows of Fig. 18 represents the complete journey of a watchman making a complete tour past the preliminary stations represented by numerals 1 to 9, the semimaster or skip stations SM and transmitting stations A to E. 50 The stations succeeding station E and ending with station A may be called tour section A, the succeeding stations terminating with station B are section B, and so on.

When the register is conditioned so that the 55 arrow 69 is pointing at the letter A at 68, and the numeral 1 at 67 is opposite lug 27, the register is conditioned for and the noses 11 and 21 are positioned to be received in the notches 92, 93 (Fig. 23) as positioned in station 1 of tour section A. 60 Thus when the register is inserted in this station the pin 58 (Fig. 8) is pushed back, unlocking the parts, the lugs 27, 39 will be held between the ribs 83, the noses 11 and 21 will be positioned to enter the notches 92, 93, the inner nose engaging the bevel 94; and all of the plunger pins 32 which protruded into perforations at that setting of the register, will respectively engage with all of the balls 86 of such station, the balls 86 of that station and the perforations 13, 14 of 70 that position of the register being characteristically identically arranged. In like manner the register positions and stations of the same indicia number are respectively identically arranged.

When the key is thus inserted the protruding 75

The resistance of the upturned end 131 against 11 to 17, other forms being shown in Figs. 20, 31 and 38 respectively.

5 The resistance of the upturned end 131 against the hook forces said front pin against said edge 144, forcing the stop plate against the stop pin 143, to hold the clockwork from unwinding until fully wound and until the V-shaped stop plate has forced the hook 134 from the winding lever, to permit the lever 130 to rise and the clockwork to operate.

10 The lower margin 146 of the guide block 136 is beveled to engage the guide pin 135 on the up-stroke to lift the guide pin to the front face of the block until the path thereof meets said edge 137 and the pin snaps against said edge. The pillar 148 (Fig. 11) stops the downward movement of the lever.

15 An inverted L lever 150, 151 (Fig. 1) having its lower part 150 secured fast on the winding shaft 132 of the clockwork, has its lateral member 151 normally disposed over an intermediate part of 20 the path of the long lug 27.

25 Said lateral member 151 moves forward of the lug 27 as the lug moves forward as the winding and actuating levers are lowered, thereby to remove itself from the cam face 153 of a stop member 154 pivoted to the bracket 112, thereby to allow the shoulder 155 to drop into the path of the long lug 27, to prevent the removal of the key until after the signal is completed and said lateral member 151 engages the cam face 153 to 30 raise said shoulder 155 from the path of the lug, the lateral member 151 then holding the member 154 in raised position.

Register trapping signal

35 It is usually desired that the register remain locked in the transmitting station during the time that the watchman is not on the tour, and that the central office be informed that the register is thus locked. This is accomplished as fol-

40 lows:

The code signal wheel 129 is toothed to give the same signal twice, as at 129', 129'', and after one set of teeth has actuated the signal contacts 160, the clockwork is automatically stopped. This is 45 accomplished by the engagement of a stop arm 161 fast on the code signal wheel shaft, with a flat spring 162 having an end 163 secured fast on the side wall of the housing. The free end is normally disposed across the path of the end of 50 the stop arm in position to stop the arm and clockwork, with the register locked therein, after one of the two signals has been sent.

55 A push button 165 (Fig. 2) on the front of the front wall has a stem 166 slidably passed through the wall, and resting on the flat spring, whereby pressure on the button pushes the spring from the stop arms and allows the second signal to be sent and the register to be released.

60 The wiring connected to the switch 160 may be as shown in said patent and need not be shown or described here.

Higher digit nose stepping disk

65 The transmitting station is operated at the end of the tour section; after the bumps 36 (Fig. 4) of the register have made a complete revolution and are ready to engage the pins 43 to release the outer nose 21, to allow the latter to be moved an increment in the transmitting station to condition the register for use in the next succeeding tour section only, and to prevent use in the other and preceding sections.

70 Herein we will illustrate and describe a number of different forms of mechanism for bringing 75 about this movement, one being shown in Figs.

11 to 17, other forms being shown in Figs. 20, 31 and 38 respectively.

75 First will be described the mechanism of Figs. 11 to 17. In this figure the movement of the outer nose is brought about by movement of a stepping disk 168 (Figs. 1 and 11 to 15) having a circular opening 169 (Fig. 14) received on said flange 123 (Fig. 11) and provided with an arcuate notch 170 (Fig. 11) adapted to receive the outer nose 21.

10 Said disk has therearound a series of front-wardly pointing pins 172 forming a pinion engaged by a stepping sector 173 (Fig. 11) pivotally mounted on a bracket 174 mounted on and offset from said back wall. The sector moves between 15 said bracket and back wall on a pivot bolt 175 rotatable in the bracket below an intermediate part of the actuating lever, said sector having peripheral teeth 176 engaged between said pins 172.

20 A radial finger 178 (Figs. 11, 16 and 17) is integral with the bolt 175, and a radial lever 179 is adjustably secured fast on said bolt by means of a pin 179' and carries a pin 180 pressed by a flat spring 181 into one of the holes 182 in the 25 sector, whereby the finger is adjustable to be engaged by an actuating pin 183 (Fig. 11) mounted on an adjustable plate 184 adjustably secured on the actuating lever 120, whereby when the inner nose 21 of the operated register causes 30 the actuating lever 120 to move down, the actuating pin 183 moves the finger 178 and rotates the sector and thereby the stepping disk an amount and a direction depending, as will be explained, upon the adjusted position of the finger 35 178 and the distance of the pin 184 from the pivot point of the sector and whether or not the pin passes between said bolt 175 and the core 108.

40 The apparatus as in Fig. 11 is for use with a tour circuit as in Fig. 18. If the transmitting station corresponds to station D, the previous stations A, B, C will each have stepped the outer nose around one increment, in a clockwise direction, in the manner now to be described, and 45 it will only be required that the station D step the outer nose one more increment in the same manner in a clockwise direction, as will now be described, to condition the outer nose for the station E.

50 This is accomplished by the disk 168 as in Fig. 14. The outer nose enters the notch 170, and it is desired that the nose be advanced in clockwise direction one increment (one-tenth of a revolution) by the operation, to condition the outer nose for station E. To accomplish this the finger 178, the pin 183 and the cam 186 must be disposed relative to the bolt 175 as in Fig. 11a. If the outer nose were to be moved counter clockwise, these parts would be placed to the right 55 of the bolt 175, as in Fig. 11.

60 To adjust the device to advance the outer nose in a clockwise direction the sector 176 is removed and replaced with the cam 186 above the bolt 175, as in Fig. 11a; the pin 183 is adjusted just under the cam 186 slightly to the left and above the bolt 175, thus to move down (when the lever 120 moves down) at the left of the bolt 175; and the finger 178 is adjusted to incline 65 to the right of the bolt 175. The pin 183 and finger are so placed, that the sector 176 and stepping disk 168 will be 70 75

moved, as will be explained, an amount just sufficient to move the outer nose one increment.

With the parts thus adjusted, the forward rotation of the register cylinder causes the bumps 5 36 (Fig. 4) to engage with, and unlock, the pins 43, and also carries down the lever 120 as above explained, whereupon the actuating pin 183 strikes the finger 178 and moves the finger a short distance out of the path of the pin, thus 10 moving the sector a small amount, and the stepping disk and nose 21 forwardly one increment in which it is locked by a pin 43 in a perforation 44 (Fig. 5) of the outer nose sleeve, the short lug 39 remaining stationary between the stop 185 15 (Fig. 2).

On the return stroke of the lever 120, the long lug returns to alinement with the short lug and a pin 43 snaps into the single perforation 45 (Fig. 6). At the same time the inner nose, which 20 is received without lost motion in the notch 124 was advanced relative to the long lug on the forward stroke, now moves back until the long lug 27 strikes the shoulder 113 holding the now advanced inner nose notch 124 and lever 120 25 against complete return to original position, the lever being thus left in the position of the dotted line 120a. At the same time, the pin 183 which left the finger 178 moves back to the position, where it left the finger. The register may now 30 be withdrawn, allowing the inner notches 124 and actuating lever 121 to be restored completely by the spring 126. This causes the pin 183 to engage the double cam 186 and move the sector 173 and outer notch 170 to original position. 35

Skip station operation

By adjusting the finger 178 and pin near to the position of the full lines of Fig. 11, the stepping disk may be backwardly rotated two or 40 more increments, to advance the outer nose from the position of station E to position for station A. This is necessary when, as in Fig. 18, less than ten tour sections are used. If only one section is omitted, the pin 183 and finger are 45 adjusted to step the disk 168 two increments; if two sections are omitted, the pin and finger are adjusted to step the disk 168 three increments.

If the register provides for ten tour sections and more than 4 or 5 are omitted, it is desirable 50 to step the disk 168 backward rather than forward, in which case the pin 183 is adjusted, for instance as in the solid lines of Fig. 11, so as to pass beyond the pivot bolt 175 on the side remote from the core 108. The pin 183 and finger are 55 adjusted to different distances from the lever 120, depending upon the number of transmitting stations omitted.

Instead of the mechanism of Figs. 11 to 17, which may move the stepping disk either forwardly or backwardly, we may prefer to use the gear mechanism of Figs. 31 to 37 which may step the stepping disk or gear 168' rearwardly any necessary number of increments.

In the signal transmitter of Figs. 31 to 37, the 60 spring raised actuating lever 120' has an enlarged inner end provided with a wide arcuate slot 187 concentric with the core 108 having gear teeth 188 on its side edge remote from the core. The stepping disk comprises a pinion 168 65 having peripheral gear teeth and is provided with the arcuate notch 170 receiving the outer nose, and is held in place by a retaining plate 189 secured over said pinion and provided with a large opening 190 exposing said notches 124, 70 75 170 in all positions.

A bracket 193 mounted on and offset from the back wall 109, carries a shaft 194 (Fig. 32) mounted between said bracket and the back wall and passing through said wide slot 187.

A driven member 195, 196 (Fig. 36) rotatably mounted on said shaft between said bracket and back wall comprises a cylindrical portion 195, and a small pinion 196 in mesh with the teeth 188 of said wide slot.

A ring gear 198, 199 rotatable on said cylindrical portion 195 has peripheral teeth 198 engaged with the teeth of the stepping pinon 168', and a forwardly disposed annular flange 199 having an inner recess 200 therein.

A forwardly projecting pin or lug 202 on said cylindrical portion cooperates with the shaft 194 to guide a slide bar 203 disposed in a plane forward of the cylindrical portion 195 and having a longitudinal slot 204 receiving said lug and shaft, whereby the bar is constrained to move angularly when the member 195, 196 rotates. Said bar carries a lock pin 205 passing through the slide bar and disposable in said recess 200.

A cam disk 207 adjustably secured stationary on said bracket 193 is provided in its rear face 25 with a spiral groove 208, 209, 210 having concentric land portions 208, 209 and a connecting steep portion 210.

Said groove receives said pin 205, and when the actuating lever 120' moves down, the lock 30 pin is in the outer land portion 208 and recess 200 and rotates the ring gear an amount depending upon the distance the lock pin moves to reach the steep portion 210 of the groove, at which portion the lock pin moves into the inner land portion 35 209 and disengages from the recess of the ring gear, leaving the ring gear and the stepping pinon at this position, a spring 211 engaging the teeth of the ring gear to hold it and the pinion 168' in such position.

As stated, the disk 207 is adjustable on the bracket 193. This permits the steep portion 210 to be placed where it will disengage the pin 205 and thus stop the stepping disk 168' after the outer nose notch 170 has moved the required 45 number of increments. Thus the stepping disk or pinion may step the outer nose any desired number of increments from one to nine by the time the lever 120' reaches the position 120a of Fig. 31.

During the upstroke of the lever and the return movement of the pin 205, the pin again reaches the recess 200 and locks the ring gear to the members 195, 196. When on the return stroke of the lever, 120', the lever moves from the position of the lower dotted lines 120' to the position 120a, it is there stopped, as explained of the lever 120. Then the register is withdrawn, and the lever 120' and stepping disk 168' return to their original positions.

In the form shown in Fig. 38, the stepping disk or pinion 168'' may be stepped either forward or backward the desired number of increments. In this form the spring raised actuating lever 120 is about the same as in Fig. 11, and a stepping disk 168' with peripheral gear teeth is about the same as in Fig. 31.

The stepping mechanism is carried on a plate 220 adjustably pivotally mounted on said back wall 109, and comprises a shaft or pin 221 carrying driven member 222, 223 mounted on the shaft and comprising a small pinion 222 and a large gear 223, the teeth of the latter being, in one position of said plate, in mesh with the teeth of said disk 168'.

5 An arcuate rack 125 pivoted to said lever is held by the spring 126 against the pinion 222 and therefore substantially coaxial with the core 108 and has gear teeth 227 on its side edge near the core and meshing with said small pinion.

10 A cam plate 230 mounted on said rack by means of bolts 231 passing through a slot 232 to be adjustable longitudinally of the rack, engages a control plate 234, pivoted on said pivoted plate and having a cam edge 235 engaged by said cam plate to throw the rack from said small gear, said control plate having a tooth 236 engageable with the teeth of said gear 223 to stop the pinion 68.

15 When the actuating lever moves down, the rack 225 rotates the pinion 222 and disk 168' an amount depending upon the position of the cam plate 230 and the distance the cam plate moves to reach the control plate to disengage the rack from the pinion, whereupon the control plate 20 234 moves to stop the pinion and stepping disk at the position that they occupy when the rack is disengaged.

25 When the lever 120 returns to normal position, the cam plate 230 disengages the control plate, permitting the rack to again engage the pinion 222, at which time, the tooth 236 disengages the gear 223 under the action of the spring 237; and when the lever 120 is restored to normal position, the stepping disk is also restored.

30 As above described, the disk was rotated in a counter clockwise direction. To rotate it forwardly we provide an idler gear 240 on said plate 220 permanently engaging with said gear 223. This gear and idler are so located on the plate 35 220 that the plate can be shifted to selectively exclusively engage the idler or the gear 223 with the stepping disk 168 to reverse the motion of the latter. A pin 241 carried by the plate 220 engages in one of two holes 242 and serves for 40 holding the pivoted plate in adjusted position.

Operation of multiple transmitter system

45 The operation of the tour system of Fig. 18 will be readily understood from the foregoing and now need be only summarized as follows:

Beginning with the register conditioned to be received by the station 1 of the tour section ending in station A, the register is inserted in that station 1 and turned in a clockwise direction until it stops. On insertion the locking pin 58 and all of the tumblers 32 of the register are pushed back by balls 86 and released from perforations, and the inner nose is freely advanced in the notch 92 an amount equal to the angle between two 50 rows of perforations, the lugs remaining stationary between the ribs 83, whereupon the tumblers snap into perforations of the next row. The register is then removed, and is in condition for the next station 2 of the same tour section. During 55 this operation, the outer nose 21 is always locked, because the bumps 36 are remote from the pins 48, and the notch 93 is positioned merely to receive the outer nose if it is in proper position, but not to rotate it relative to the lugs 27 and 39.

60 The position of the notch 93 is the same for all stations of the same tour section.

This action is repeated for each preliminary station 2, 3 and 4, which conditions the register for the semi-master station SM. The key is inserted in this station as in the other preliminary stations, but because of the long inner notch 92 and the sufficiency of balls 86, the inner nose may advance, in this case, five increments, thereby to condition the register for station A.

65 The register is then inserted in station A and

turned forward, carrying the long lug forwardly slightly until the tumblers thereof meet the balls 110 and are released, whereupon the antifriction ball 116 (Fig. 1) yieldably holds back the long lug one increment while the inner nose 11 5 engages the inner notch 124 and carries downwardly the lever 120 or 120' (Figs. 11, 31 or 38) winding the clockwork. This action is continued until the lever is stopped against the pillar 148. At the same time, the bumps 36 release the pins 10 43, and the pin 183 (Fig. 11) or 205 (Fig. 31) or the plate 230, properly positioned causes the rotation of the stepping disk 168 or 168' and the rotation of the outer nose 21 one increment.

15 The key is then released and the clockwork unwinds until one signal is sent and the signal wheel is stopped by the spring 162 (Fig. 1). Later the button 165 is pressed and the other signal is sent.

During the unwinding the lever 120, the long lug 27 and the stepping disk 168 move back to 20 initial position, and the noses retain their new position relative to the long lug.

Because the long lug has now been pushed back relative to the inner nose in the notch 124, the long lug strikes the shoulder 113 and holds the 25 lever 120 against return until the register is withdrawn, whereupon the notches move back to their original positions, in which the noses in the new position cannot be received.

30 The operation of the rest of the tour system of Fig. 18 is similar to that just described except that the station E must advance the outer nose several increments, and there is no semimaster just before the station B. Before station B, the stations 6 to 9 merely continue to advance the 35 inner nose in the same manner described of stations 1 to 5, thus conditioning the register for station B.

When the register reaches station E, the pin 183 or 205 or the plate 230 which has been adjusted to turn back stepping disk 168 or 168' the required amount, turns the stepping disk in a counter clockwise direction until the outer nose is conditioned for the tour section ending in station A. With the arrangements shown in Figs. 45 11 and 38, the transmitting station may be adjusted and adapted to move the outer nose either forwardly or backward; and when stations are omitted it is thus possible to move the stepping disk in that direction which requires the least 50 movement.

Single transmitter system

55 The tour system of Fig. 19 requires only one transmitting station T shown in combination 55 with tour sections a to j. In this system the watchman is required to come back to the same transmitting station after each tour section, and means are provided for moving both noses 11 and 21 and also the stepping disk 168 (Fig. 20) one 60 step each time the transmitter is operated, thereby to condition the register for the next section and to prevent the reuse of the transmitting station until the stations of said next tour section have been visited.

65 To this end, the stepping disk 168 (Fig. 20) is made completely rotatable against the actuating lever 120, has an opening received on said flange 123 and is provided with an arcuate notch 170 for receiving the outer nose 21. Around said disk 70 is a series of forwardly pointing pins 172 forming a ratchet wheel. A spring pressed advancing pawl 250 pivotably mounted on the lever is adapted to successively engage the pins and advance the disk and outer nose one increment near the 75

close of each lever stroke. A detent pawl 251 pivotally mounted on the backwall 109 has a rounded end 252 adapted to be pressed by the spring 253 between said pins to hold the disk 5 against accidental movement.

Operation of single transmitter system

With the notches 124 and 170 positioned to receive the noses as the register comes from the 10 tour section *a*, the operation of the system of Fig. 19 is as follows:

The tour section *a* is completed as described of Fig. 18, and the register is inserted in station T and rotated forwardly thus bringing the bumps 36 15 against and unlocking the pins 43 and then carrying down the lever 120, setting the inner nose 11 forward one increment relative to the long lug 27 and winding and setting off the clockwork as described of Figs. 1, 11 and 18. When 20 the lever 121 begins its downward movement, the pawl 250 engages a pin 172 and steps the disk 168 and outer nose forward one increment so that a pin 43 snaps into the next perforation 44 (Fig. 5) to lock the outer nose relative to the short lug 39 25 which is also held stationary by the stops. At this time the pawl 25 engages the pin 255 and is thereby pushed off of the pin 172. Thus the outer nose, after shifting one increment, then remains stationary, relative to the short lug, in the new 30 position. However, there is only one perforation 45 (Fig. 6) on the long lug member, and the long lug does not become fast with the short lug, and consequently the outer nose, until the long lug is brought back, after the signals, to position of 35 alignment with the short lug. The pawl 251 then yieldably holds the stepping disk against accidental displacement.

After the completion of the two signals as previously described, both noses have been stepped 40 forward one increment relative to the lugs, and the stepping disk has been stepped forward one increment.

It is noted that the inner nose has been stepped 45 forward one increment relative to the long lug, and when the long lug returns to contact with the shoulder 113 (Fig. 1), the inner nose and its notch 124 are still one increment further in a clockwise direction and the notch 124 has therefore not returned to its original position. The 50 key is then withdrawn with the nose in the advanced position, after which the clockwork unwinds further and restores the notch 124 to its original position where it cannot receive the inner nose in its new position relative to the long lug until said nose is again conditioned therefor by 55 successive engagement with the stations of the next tour section.

The operation of the next tour sections are 60 similar to the one described, and each tour section brings the long lug back to the normal position relative to the inner nose, so that the inner nose may enter the notch 124 to permit the register again to operate the transmitter and advance the outer nose notch 170 an increment 65 after each tour section, until the stepping disk has made a complete cycle as all of the tour sections have been visited.

We claim as our invention:

1. In a tour system a register having a first, second and third part, all movable to three or more positions relatively to each other to condition the register for operation in different stations; and a series of stations each having characteristically placed conditioning means for conditioning a properly conditioned register for the

next succeeding station, and engageable with all of said parts for preventing such conditioning of a register when the register is not conditioned for such station; all of said conditioning means having different positions in certain stations. 5

2. In a tour system a register having a first, second and third part movable relatively movable to each other to condition the register for a station, a plurality of characteristic means for locking the first and third parts together in a 10 plurality of different positions, means for locking said second part with one of the others and unlocking it only when said others are at a certain predetermined position of relative adjustment; a series of stations each having characteristic 15 means engaging said parts for conditioning the register for the next succeeding station; one or more of said stations having means for moving the first and second parts different distances relative to the third part for conditioning said 20 parts for another station.

3. In a tour system a register having a first, second and third part, all movable in endless paths respectively relatively to each other to condition the register for operation in different 25 stations; a series of stations each having characteristic means for conditioning a properly conditioned register for the next succeeding station; one or more of said stations having means for adjusting each of said parts to different positions 30 relative to the other two for conditioning the register for another station, maintaining them in such condition as the register is withdrawn from such station.

4. In a tour system a register having a first, 35 second and third part, all movable relatively to each other to condition the register for operation at different stations; and a series of stations each having characteristic means for conditioning a properly conditioned register for the next suc- 40 ceeding station, and engageable with said parts for preventing such conditioning of a register when the register is not conditioned to for such station; one or more of said stations being a signal station having means controlled by a properly 45 conditioned register for causing a signal, and means for conditioning the register for the next succeeding station; one or more of said stations having conditioning means therein to change the position of adjustment which all of said parts have to each other as they come to said conditioning means, and effect new positions of adjustments of all of said parts relative to each other; and means to maintain said new positions as the register is withdrawn from the station. 55

5. In a tour system a register having a first, second and third part movable relatively to each other, when in a proper station, to condition the register for a next succeeding station; a series of stations each having characteristic means for conditioning a properly conditioned register for the next succeeding station; one of said stations being a signal station having a transmitter controlled by a properly conditioned register for causing a signal, and means for moving two of 60 said parts to new different distances from the other part for conditioning the register for another station, and maintaining them in such new positions as the register is withdrawn.

6. In a tour system, the combination of a key 70 having a first and second nose and a lug all movable relatively to each other for conditioning the key, a plurality of characteristic means for locking the lug and first nose together, means for locking the first and second nose and lug 75

- together, and means for automatically unlocking them at a certain predetermined position of adjustment of the lug relative to the first nose; a series of stations each having characteristic 5 stop means engageable with the lug and noses for preventing the insertion of the key when the key is not conditioned to be received by such station, and means cooperative with said characteristic means for unlocking the lug when the key 10 is conditioned for the station, said stop means serving, when the key is operated, to effect relative movement between the lug and the first nose to condition the key for the next succeeding station; one or more of said stations being a transmitting station adapted to receive the key when 15 conditioned therefor and in said certain position of adjustment, such transmitting station having a transmitter controlled by the key, means for conditioning the lug and first nose for the next 20 succeeding station, and means actuated by the first nose for moving the second nose to condition it for the next succeeding station.
7. In a tour system, a register having a first, second and third part adjustably movable relatively to each other to condition the register for insertion into a station; a plurality of characteristic means for locking the first and third parts immovably together; means for unlocking the first and third parts from each other; means for locking said second part immovably with one of the others and unlocking it when said others are at a certain single exclusive predetermined position only of relative adjustment.
8. A register key comprising a handle carrying a nose; a lug and a second nose relatively rotatable to each other and the first nose; a plurality of characteristic means, each unlockable, for locking the lug in different positions of adjustment relative to the handle; means for locking the second nose relative to the handle; and means carried by the handle for unlocking the second nose when the lug is in one position relative to the first nose.
9. A register key comprising a cylinder having 45 perforations in longitudinal groups; an actuating nose at the inner end of the cylinder; a sleeve rotatable on said end and having a higher digit nose and perforations disposed around the cylinder; a long lug comprising a portion rotatable on the cylinder and having a perforation at the inner end; tumblers yieldably protruded from said lug into perforations of the cylinder; a short lug rotatable on said sleeve and portion; plunger members yieldably protruded from said 55 short lug into the perforations of said sleeve and portion; and bumps on the cylinder positioned to engage said plunger members at one position of the long nose on the cylinder to unlock the short lug from said sleeve and portion.
60. 10. A register key comprising a cylinder having perforations therein; a handle and a shell on the outer end of the cylinder; an actuating nose at the inner end of the cylinder; a sleeve rotatable on said end and having a higher digit 65 nose and perforations disposed around the cylinder; a long lug comprising a portion rotatable on the cylinder and having a perforation at the inner end; tumblers yieldably protruded from said lug into perforations of the cylinder; a short lug member rotatable on said sleeve and portion having a short lug thereon; plunger members yieldably protruded from said short lug into the perforations of said sleeve and portion; bumps on the cylinder positioned to engage said plunger 70 members at one position of the long nose on the 75
- cylinder to unlock the short lug from said sleeve and portion; station indicia around the shell to indicate the position of the long lug; and tour section indicia around the sleeve and an index on the short nose member to indicate the position of the higher digit nose. 5
11. A signal transmitter comprising a pivoted actuating lever revolved by a key; a transmitter clockwork; a winding means to wind the clockwork; a pawl on the actuating lever and adapted 10 to engage with the winding means to wind the clockwork; and means to force the pawl from the winding lever and hold the clockwork from unwinding until fully wound and the pawl is forced from the winding means. 15
12. A signal transmitter comprising a casing having a keyhole adapted to receive a key; a pivoted actuating lever revolved by said key; a transmitter clockwork; a winding lever actuated by said lever to wind the clockwork; a hook pawl 20 on the outer end of the actuating lever and adapted to engage with the winding lever as the actuating lever moves down, thereby to wind the clockwork; a stop pin on a movable part of the clockwork; a pivoted member engaged by the 25 pawl to force the pawl from the winding lever and to force the member against the stop to hold the clockwork from unwinding until fully wound and the pawl is forced from the winding lever. 30
13. A signal transmitter comprising a casing having a keyhole adapted to receive a key; a transmitter clockwork having a shaft carrying a code signal wheel bearing duplicate signals; a winding means actuated by said key to wind the clockwork; a stop on the code signal wheel shaft; 35 a spring disposed across the path of the stop in position to stop clockwork after completion of one of the signals; an exteriorly operable push to push the spring from the stop. 40
14. In a signal transmitter, the combination 45 of an actuating lever having a nose-receiving notch and a rack coaxial with the pivot point of the lever; a stepping pinion provided with a nose-receiving notch; a rotary driven member having a cylindrical portion, and teeth in mesh with said rack; a ring gear rotatable on said cylindrical portion and engaged with the stepping pinion, and having an annular flange having an inner recess therein; a slide bar guided diametrically of said member; a lock pin mounted on the slide bar and disposable in said recess; and a cam disk 50 adjustably fixedly secured coaxial with said member and provided with a spiral groove receiving said pin and having concentric land portions and a connecting steep portion, whereby when said member rotates, the lock pin rotates the ring gear an amount depending upon the distance the lock pin moves to reach said steep portion, at 55 which portion the lock pin disengages from the ring. 60
15. In a signal transmitter, the combination 65 of an actuating lever having a nose-receiving notch; a stepping disk having peripheral gear teeth and a nose-receiving notch; a supporting plate; a driven member rotatably mounted on said plate and comprising a small pinion, and a large gear adapted to mesh with said disk; an arcuate rack pivoted to said lever and yieldably pressed to mesh with said small gear; a cam plate longitudinally adjustable on said rack, a control plate pivoted on said supporting plate and having a cam tooth and engageable by said cam plate to throw the rack from said small pinion, and movable by said cam plate to throw said tooth 70 into the teeth of the pinion to stop the pinion. 75

16. A transmitter as in claim 15 comprising an idler gear on said supporting plate engaging with said pinion; means for pivotally mounting said supporting plate to move the supporting plate as to selectively exclusively engage the idler or the large gear with the stepping disk; and means for holding the supporting plate in adjusted position.
17. In a tour system, a register having a first, second and third part, all cyclically movable always in the same direction relatively to each other to condition the register for operation in different stations; and a series of stations each having characteristically placed conditioning means for conditioning a properly conditioned register for the next succeeding station, and engageable with all of said parts for preventing such conditioning of a register when the key register is not conditioned for such station; all of said conditioning means having different relative positions in respective stations.
18. In a tour system a register having a first, second and third part, all completely rotatably movable relatively to each other to condition the register for operation in different stations; and a series of stations each having characteristically placed conditioning means for conditioning a properly conditioned register for the next succeeding station, and engageable with all of said parts for preventing such conditioning of a register when the key register is not conditioned for such station; all of said conditioning means having different relative positions in respective stations.
19. In a tour system, a register key having a first, second and third part adapted for adjustment relatively to each other, when in a proper station, to condition the key for a next succeeding station; a series of stations each having characteristic means for conditioning a properly conditioned key for the next succeeding station; one of said stations being a signal station having a transmitter controlled by a properly conditioned key for causing a signal; and means for effecting different relative positions of all of said parts relative to each other as received at one station and maintaining said relative positions for conditioning the key for another station.
20. In a tour system, a key having a first, second and third part adjustably movable relatively to each other to condition the key for a station; means for relatively adjusting said parts; a plurality of characteristic means for locking the first and third parts together in relative adjustments; means engageable with said characteristic means for unlocking said first and third parts when in one predetermined adjustment and to place the first and third part in different predetermined relative adjustment; means for locking said second part with one of the other parts and unlocking it when said other parts are at a certain single exclusive predetermined position of relative adjustment.
21. A register key comprising a cylinder having perforations therein; a handle and a shell on the outer end of the cylinder; an actuating nose at the inner end of the cylinder; a sleeve rotatable on said end and having a higher digit nose; a long lug comprising a portion adjustably rotatable on the cylinder; a short lug member adjustably rotatable on said sleeve and portion having a short lug thereon; station indicia around the shell to indicate the position of the long lug; and tour section indicia around the sleeve and an index on the short nose member to indicate the position of the higher digit nose.
22. In combination, a key having a fixed nose and a lug and an adjustable nose adjustable thereon; means for locking the adjustable nose and lug in adjusted relative positions; a preliminary station comprising a housing having a key-hole; means in the housing for supporting the key for axial rotation; stops in the housing for holding the key lug against rotation; means in the casing for unlocking the lug from the key body when the key is moved in forward direction, and means secured in the housing and provided with two openings adapted respectively to receive the adjustable nose snugly and the fixed nose snugly when placed in proper position, and allow a lost-motion of the fixed nose as great as the angle the fixed nose is to be advanced.
23. In combination, a station comprising a casing; a register key adapted to be received by the casing and having a lug, a first nose, a second nose and means for locking them in various relative positions, means in the casing to unlock the first nose from the lug; means in the casing to move said lug to a next position as the key is moved forwardly; an actuating member moved by the first nose; and means in the casing actuated by the actuating member to rotate the second nose.
24. In combination, a station comprising a casing; a register key adapted to be received by the casing and having a lug, a first nose, a second nose and means for locking them in various relative positions, means in the casing to unlock the first nose from the lug; means in the casing to move said lug to a next position as the key is moved forwardly; an actuating member moved by the first nose; and adjustable means in the casing actuated by the actuating member to rotate the second nose different distances according to the adjustment.
25. In combination, a station; a register key adapted to be received by the station and having a first nose, a second nose and means for locking them in various relative positions; said station comprising means for unlocking the noses; an actuating member actuated by the first nose; a stepping member provided with a recess adapted to receive the second nose; and an advancing pawl on the actuating member adapted to engage and advance the stepping member.
26. A register key comprising a lug rotatable on the key for conditioning the key for a station; a locking means movable for locking the lug and key together when the locking means is in one position and unlocking them when the means is in another position; and movable means for locking the locking means and holding it against movement.
27. A register key comprising a handle; a cylinder carried by the handle; a lug rotatable on the cylinder for conditioning the key for a station; a locking means movable for locking the lug and cylinder together when in one position and unlocking them when in another position; and means movable for locking the locking means and holding it against movement.
28. In combination, a preliminary station having a back stop plate provided with a key pivot means; a core therein, and two arcuate notches coaxial with the core; a key received by the pivot means and having relatively movable noses receivable in the notches, said notches having different angular lengths relative to the respective noses received therein.
29. In combination, a key having a lug and a pair of relatively movable noses; a housing having

ing a keyhole; a cylindrical core in the housing coaxial with the keyhole; a pair of angularly spaced fixed stops in the housing offset from the core between which the lug is disposable; the rear of the housing being provided with two articulate openings adapted to receive the noses, one of the openings being long enough to allow angular movement of the nose therein.

30. In combination, a key having a first, second and third relatively movable parts; a housing having a keyhole; means to pivot the key in the

housing coaxial with the keyhole; means to hold the first and second part against rotary movement relative to the housing; the rear of the housing being provided with an opening adapted to receive the third part and allow limited angular movement of the third part relative to the pivot axis.
